UNITED STATES PATENT OFFICE.

WENCESLAS V. JEAN, OF MINNEAPOLIS, MINNESOTA.

ORE-REDUCING APPARATUS.

No. 926,492.

Specification of Letters Patent. Patented June 29, 1909.

Application filed October 10, 1907. Serial No. 896,865.

To all whom it may concern:

Be it known that I, WENCESLAS V. JEAN, of Minneapolis, Hennepin county, Minnesota, have invented certain new and useful Improvements in Ore-Reducing Apparatus, of which the following is a specification.

My invention relates to ore separating devices in which an electric current is employed as a reducing agent.

The object of my invention, is to provide means for reducing metals to a non-adhesive pelvaceous form.

My invention consists generally in various constructions and combinations, all as hereinafter described and particularly pointed out in the claims.

In the accompanying drawings forming part of this specification, Figure 1, is a vertical sectional view of an ore separating apparatus embodying my invention. Fig. 2 is a top view of the same. Figs. 3 and 4, are detailed views of the agitating paddles. Fig. 5 is a detail view of one of the carbon plates. Fig. 6, is a detail view illustrating the manner of supporting the carbon plates.

In the drawings, 1, represents the tank or receptacle divided into compartments A and B by a partition 6, preferably of cloth. In one of these compartments (A) are placed a number of paddles so arranged that part of them revolve in the direction of the hands of a clock and the rest counter-clockwise. The blades of these paddles are all inclined so as to produce an upward movement of the liquid in tank when paddles are in motion. The bottom paddles (2) are provided with means for the passage of air through them into the solution, said air passing into the shaft, which is hollow at (11) and by means of suitable connections, through the paddles into the solution as shown in the drawings at (Fig. 4). The upper paddles (3) are not provided with means for the passage of air, but the shaft of the upper paddles, which incloses the shaft of the lower paddles, has a section of its circumference removed, as shown at (Fig. 3.) to allow the passage of air from the hollow inner shaft which is provided with a number of small holes in its length for that purpose as shown in the drawings at (Fig. 4). A number of carbon plates (4) are arranged around and close to the shaft, said plates being connected with positive pole of electric generator by means of binding-

post (8) and forming the anode. These plates are fastened to a metal ring (10) as shown in drawing at (Fig. 6). A number of carbon plates (5) are suspended in compartments (B) and separated from previously described carbons by means of said cloth partitions (6). These carbon plates are connected to the negative pole of the electric generator by means of binding-post (9) and form the cathodes.

In practice the compartment (A) is filled with a suitable chemical solution, with which is mixed a quantity of ore to be reduced; the liquid will pass through cloth partitions into compartments (B) but the ore will be prevented from passing into these compartments by the cloth partition (6). The paddles are now set in motion which produces a violent agitation of the liquid in compartment (A); the air is turned on, which drives the ore toward the circumference of the tank and also keeps the ore from settling on the bottom. The electric current is turned on, which, passing through the solution, decomposes it, depositing the metal in a non-adhesive form on the cathodes (5) from which it falls into suitable receptacles (7) placed beneath the cathodes to receive it. It will be readily seen that while the solution in compartment (A) is violently agitated the solution in compartment (B) will be practically at rest, owing to the intervention of the cloth partitions (6), consequently the metal when deposited on the cathodes (5) will readily fall to the bottom as it cannot adhere to the cathodes and the circulation in these compartments is not sufficient to keep it suspended in the solution. An electro-motive force of fifteen (15) to twenty (20) volts is required to produce the best results.

Claims—

1. An ore separating apparatus, comprising a tank, a screen dividing the interior thereof into an inner and outer compartment concentrically arranged, anodes and cathodes in said compartments respectively and having suitable terminals for electric connections, agitators provided in said inner compartment and having means for delivering currents of air into the lower portion of said compartment, for the purpose specified.

2. An ore reducing apparatus, comprising a tank, having an inner and an outer compartment and a perforated wall between them, anodes and cathodes depending within said compartments respectively and having

suitable terminals for electric connections, a hollow shaft concentrically arranged within said inner compartment, hollow arms radiating therefrom and having a series of perforations, means for revolving said arms and said shaft having a connection with a fluid pressure supply whereby currents of air will

be discharged into said inner compartment through said hollow arms, substantially as described.

WENCESLAS V. JEAN.
